UNITED STATES PATENT OFFICE.

JULIAN LOUIS LEFEBVRE AND CHARLES SAMUEL UPTON, OF EUREKA JUNCTION, WASHINGTON.

FORCE AND LIFT PUMP.

SPECIFICATION forming part of Letters Patent No. 569,047, dated October 6, 1896.

Application filed May 23, 1896. Serial No. 592,776. (No model.)

To all whom it may concern:

Be it known that we, JULIAN LOUIS LEFEBVRE and CHARLES SAMUEL UPTON, of Eureka Junction, in the county of Walla Walla 5 and State of Washington, have invented a new and Improved Force and Lift Pump, of which the following is a full, clear, and exact description.

The object of the invention is to provide a 10 new and improved force and lift pump which is simple and durable in construction, very effective in operation, and arranged to throw or lift a continuous stream of water.

The invention consists principally of a 15 plunger-barrel containing two reciprocating plungers, separated one from the other by a packing fixed in the barrel, a suction-pipe having a valve and extending from the lower end of the barrel, a valved pipe leading from 20 the suction-pipe above its valve to the barrel above the uppermost plunger, and a second valved pipe leading from the suction-pipe below its valve to the barrel between the upper plunger and said packing.

25 The invention also consists of certain parts and details and combinations of the same, as will be fully described hereinafter, and then pointed out in the claims.

Reference is to be had to the accompanying 30 drawings, forming a part of this specification, in which similar characters of reference indicate corresponding parts in all the figures.

Figure 1 is a sectional side elevation of the improvement. Fig. 2 is a similar view of the 35 same with the plungers in a different position. Fig. 3 is a side elevation of the skeleton part of the plungers, and Fig. 4 is a side elevation of the lower end of the suction-pipe.

The improved pump is provided with a 40 barrel made in two sections A A', connected with each other by a T A^2 , and on the upper end of the section A' screws a T A^3 , connected with a discharge-pipe B. The lower end of the barrel-section A is formed with a T A^4 , 45 supporting a suction-valve C, connected at its lower end with a suction-pipe D, adapted to extend with its lower perforated end D' into the water or other liquid to be lifted.

In the barrel-sections A A' operate the 50 plungers F F', of which the plunger F' is provided with a valve for the passage of the

water, as hereinafter more fully described. The plungers F F' are rigidly connected with each other by a stem F², which passes through a packing G, held in the upper end of the 55 barrel-section A. The upper plunger F' is connected with a plunger-rod F³, extending upwardly through the discharge-pipe B, to connect at its upper outer end with a suitable mechanism for imparting the usual re- 60 ciprocating motion to the plungers F F'.

From the suction-pipe D, below the valve C, extends pipe H, having a check-valve H' and connecting with the T A^2 , as plainly shown in the drawings, and from the T A^4 leads a 65 pipe I, likewise provided with a check-valve I' and connecting with the T A^3 on the upper end of the barrel A'.

The plunger F' is made with two cylindrical parts F⁴ F⁵, screwed together, as plainly shown 70 in Fig. 2, the upper end of the part F⁴ carrying a valve F⁶, adapted to open upward on the downstroke of the plunger F'. On the parts F⁴ F⁵ are rings F⁷ F⁸, arranged alternately, and of which the rings F⁷ are prefer- 75 ably made of leather and the rings F⁸ of metal, so as to insure a proper packing of the plunger F' in the barrel A'. The fixed packing G is similarly constructed and is made of two parts G' G², screwed together and carrying 80 alternately-arranged leather rings G⁴ and metal rings G⁵, of which the leather rings G⁴ fit into an enlarged portion or seat in the upper end of the barrel-section A.

In the parts G' G² is arranged a rubber 85 packing G³, through which passes the stem F². Directly below the fixed packing G are arranged air-openings A⁵, formed in the wall of the barrel-section A, to permit the air to pass in and out of the said barrel-section on 90 the up-and-down movement of the plunger F. Now when the plungers F F' are on the up-stroke, as illustrated in Fig. 1, then water is drawn in through the suction-pipe D, the water passing through the valve C into the 95 lower part of the barrel-section A, the water also passing from the suction-pipe D up the pipe H and past the valve H' into the T A^2 and the lower part of the barrel-section A'. On the downstroke of the plungers F F' the 100 water previously drawn in at the lower end of the barrel-section A is forced by the plunger

- F up through the pipe I into the discharge-pipe B, and the water in the lower part of the section A' is forced up through the plunger F' and past its valve F⁶ into the upper end of the barrel-section A' and the discharge-pipe B. On the next upward stroke of the plungers water is again drawn into the several parts, as above described, it being understood that on this upward stroke the water above the plunger F' is forced upward and lifted through the pipe B to the discharge. Thus a continuous stream of water is lifted or forced on each up or down stroke of the plungers F F'.
- 15 The pump is very simple and durable in construction, not liable to get out of order, and can be readily repaired, as the several parts can be taken apart even by unskilled persons.
- 20 It is understood that the leather rings G⁴ readily expand in the enlarged seat in the barrel-section A, so as to form a very firm packing.
- Having thus fully described our invention, 25 we claim as new and desire to secure by Letters Patent—
1. A force and lift pump, provided with a barrel having an enlarged seat, a packing made in parts and containing a central packing for the passage of the plunger-stem, and alternately-arranged exterior leather rings and metal rings, of which the leather rings are adapted to expand into the enlarged seat, substantially as shown and described.
- 30 2. A pump having a barrel formed in two

sections, a T connecting the sections, a pipe extending from the T longitudinally with the barrel to one end of the same, a second pipe extending longitudinally with the barrel from one end of the same to the other, a packing 40 held stationary within the inner end of one section of the barrel, a rod reciprocal through the packing, two plungers fixed to the rod and respectively located on each side of the packing, a valve in the lower portion of the 45 barrel, and a valve in each pipe, all of said valves opening upward, substantially as described.

3. A pump having a barrel formed in two sections, a T connecting the sections, an additional T at each outer end of the sections, a valve communicating with the lowermost T, a suction-pipe projecting from the valve, a pipe extending from the first or intermediate T to the suction-pipe, an upwardly-opening valve within the pipe which extends from the said T, a second pipe extending from and communicating with each of the remaining T's, an upwardly-opening valve in the second pipe, a packing within the upper portion of 60 the lower section of the barrel, a rod movable through the packing, and two plungers carried by the rod, the plungers being respectively located on each side of the packing, substantially as described.

JULIAN LOUIS LEFEBVRE.
CHARLES SAMUEL UPTON.
